W. E. GUINA

LOOSE LEAF BINDER

Filed August 25, 1924

FIG. 1.

FIG. 2.

FIG. 3.

INVENTOR:

BY WILLIAM E. GUINA

W. E. Guina
ATTORNEY

UNITED STATES PATENT OFFICE.

WILLIAM E. GUINA, OF DETROIT, MICHIGAN, ASSIGNOR TO THE W. S. GILKEY PRINTING COMPANY, OF CLEVELAND, OHIO, A CORPORATION OF OHIO.

LOOSE-LEAF BINDER.

Application filed August 25, 1924. Serial No. 733,998.

My invention relates to loose-leaf binders, its object being to provide a binder simple in construction and of operation.

The said invention consists of means hereinafter fully described and particularly set forth in the claim.

In the annexed drawing:

Figure 1 represents, in perspective, a loose-leaf binder embodying my invention, the cover being shown open.

Fig. 2 represents, upon an enlarged scale, a transverse section.

Fig. 3 represents, on said enlarged scale, an end elevation.

The illustrated embodiment of my invention includes a rectangular cover consisting of a stiff bottom cover-member 1, a stiff top cover-member 2, and a back member 3 to which the two members 1 and 2 are hinged or flexibly connected.

At equal distances from the ends of bottom-member 1, are secured one end 4 of each of two coiled springs 5, by means of suitable fasteners such as rivets 6. These springs are coiled around the straight body portion of a rod 7 whose two ends are each formed with a hook-shaped member 8, each of whose planes are angularly related to the axis of the body portion of the rod, preferably right-angularly. Said axis lies parallel with the edges of the cover.

The other ends 9 of said springs are secured, as shown, to the base portion of said member 8, respectively.

The outer ends of said member 8 are free, as shown.

The springs therefore act as pivots for the rod and members 8 and tend to hold same in their closed position as shown in full lines in Fig. 2.

When it is desired to secure a set of loose leaves, one of the hooks 8 is grasped and raised to assume the position shown in dotted line in Fig. 2, whereupon the set of leaves 10 is placed in position, and the hook released. The free ends of said hooks will thereupon impinge upon the uppermost leaf and hold the entire set securely in place. The outer or free ends of the hooks are preferably made blunt, as shown, so as not to injure the surface of the uppermost leaf. To remove a sheet or sheets, the reverse of the above operation is affected.

What I claim is:

A loose-leaf binder comprising the combination with a suitable cover; of a sheet-fastener consisting of a rod resting upon the inside of the cover and bent at its two ends to form two hook-shaped members whose planes are substantially at right angles to the axis of the rod, and two springs coiled about the said rod and respectively adjacent to said hook-shaped members, one end of each such spring secured to said cover and the other end to the adjacent hook-shaped member, the axis of said rod being parallel with the said cover, said springs alone serving as a pivotal connection of the rod with the cover and as a resilient means to press the hooks into closed position.

Signed by me this 30th day of July, 1924.
WILLIAM E. GUINA.
